UNITED STATES PATENT OFFICE

2,421,888

DIFFUSER FOR CENTRIFUGAL BLOWERS

Thomas Jackson, North Muskegon, Mich., assignor to Continental Motors Corporation, Muskegon, Mich., a corporation of Virginia

Application May 27, 1942, Serial No. 444,695

1 Claim. (Cl. 230—132)

1 My invention relates to internal combustion engines and more particularly to a cooling system for same, and applicable especially with an engine of the horizontal opposed cylinder type.

Much difficulty has been experienced in air cooling internal combustion engines of the horizontal opposed cylinder type, especially when such engines are used in power plants other than aeronautical, due principally to the fact that there is a minimum air circulation induced by movement of the power plant through the air. It is thus necessary to provide some additional means for inducing the flow of an adequate circulation of cooling air around the engine cylinders, and for controlling of the air flow, in order that maximum cooling may be had.

An object of my present invention is to facilitate engine performance by constructing means inducing a circulation of cooling air around all the engine cylinders and obtaining a maximum cooling of the engine by providing an improved cowling structure and blower assembly.

Another object of my present invention is to facilitate the circulation of cooling air over the finned cylinders of an internal combustion engine by providing an improved blower construction including a blower housing having outlets constructed and arranged to facilitate the exhausting of air from the blower housing thereby facilitating air circulation over the engine cylinders.

A further object of my present invention is to improve engine performance by providing an improved air cooling cowling structure for said engine, which structure includes an external hood portion enclosing all engine cylinders and internal baffling portions defining passages which confine the circulation of cooling air in proximity with the cylinder fittings.

Still further objects of my present invention relate to various details of construction including the means for clamping or otherwise securing the cowling structure to the engine.

For a more detailed understanding of my invention reference may be had to the accompanying drawings illustrating a preferred embodiment of my invention, in which like characters refer to like parts throughout the several views, and in which:

Fig. 1 is a plan view of an engine of the horizontal opposed cylinder type and illustrating in plan the cowling structure and blower assembly,

Fig. 2 is a side view thereof illustrating the detailed construction of the cowling structure,

Fig. 3 is an end view of the blower housing,

2

Fig. 4 is an enlarged detail sectional view through the blower housing taken substantially on the line 4—4 of Fig. 1.

Fig. 5 is a plan sectional view through said engine cowling structure showing the internal cylinder baffles, and

Fig. 6 is a fragmentary detail sectional view of said internal cylinder baffle construction.

The present cooling system is particularly constructed for assembly with an internal combustion engine A of the horizontal opposed cylinder type. 10 indicates the engine crankcase structure and 11 indicates the opposed cylinders to which are secured the cylinder heads 12. Each 15 of the cylinders carries a plurality of annular cooling fins 13.

The fly-wheel housing 14 is secured to the end of the engine and carries suitable brackets 15 by which same is supported. This flywheel housing is provided with a blower housing portion 16, having a plurality of outlets 17 about its periphery.

The cowling structure 20 includes an external hood structure 21 constructed and shaped to 25 overlie and substantially house all said engine cylinders. The hood structure aforesaid is secured to the flywheel and blower housing by suitable bolts or other fastening devices 22, and includes a longitudinally extending tunnel 23 overlying the engine and which communicates with an 30 annular ring tunnel 24a, same having suitable outlets 25a communicating with the interior of the blower housing. This hood structure is open on the underneath side and the cooling air is 35 caused to flow about said engine cylinders in the general direction as indicated by arrows 24 and 25, or in other words, substantially upwardly past the finned engine cylinders.

In the cooling means of the character described it is necessary that the cooling air flow 40 in contact with the finned engine cylinder, and in the present device this is preferably accomplished by providing means which confine the flow of cooling air to a path adjacent to said 45 cylinder fins. This is preferably accomplished by suitable baffles 26 which are clamped, by means of a bolt 27 and a spring wire clamp 28, to fit around the peripheral edge of the cylinder fins (see Fig. 2). The dotted arrows indicate generally 50 the path of the stream of air flowing about the engine cylinders and arrows 25 indicate how the air flows from the outlet of the air passages defined by these baffles 26 into the annular ring conduit 55 as indicated by arrows 29 and then subsequently

into the blower housing as indicated by arrows 30.

It will be noted that the baffles 26 are securely clamped about the engine cylinders by means of these spring wire clips 28, same being hooked as at 31 to the baffle, and yieldingly engaged at a mid-portion 32 with the engine cylinder. Suitable brackets 33 are provided for supporting these baffles by the external hood structure.

The outlets 17 of the blower housing 16 are formed by triangularly shaped integral bridge portions or transverse bars 40 which are substantially equally annularly spaced about the entire peripheral surface of the blower housing. One side of each of these triangularly shaped bridge members or bars 40 lies substantially flush with the peripheral surface of the blower housing and the said other two sides of the housing bars 40 are preferably inclined somewhat to a radial plane as indicated by the dot and dash line P—P (see Fig. 4).

One of said two sides designated 42 is straight while said other side 43 is convex. The air flows radially outwardly of the blower housing through the outlet openings 17 as indicated generally by arrows 44. The relatively wide mouth of the discharge or outlet openings 17 is indicated at 45, and the outlet of said opening is indicated at 46. At an intermediate portion of the outlet or discharge opening 17, there is a restricted portion 47, which thus forms a venturi which facilitates the discharge of air outwardly of the blower housing, thereby materially increasing the efficiency of the air flow and the circulation of the cooling air about the engine cylinders.

Although I have illustrated but one form of my invention, and have described in detail but a single application thereof, it will be apparent to those skilled in the art to which my invention pertains, that various modifications and changes may be made therein without departing from the

spirit of my invention or from the scope of the appended claim.

I claim:

5 In a radial blower housing, a series of openings formed by circumferentially aligned transverse bars annularly spaced around the blower rotor, the bars having a three-sided cross-sectional configuration such that one side of each bar lies in the surface of a cylinder which is common to all the bars, one other side of each bar within the openings extending toward an adjacent bar to create a restricted portion in each opening having smaller dimensions than the opening at the surface of the aforesaid cylinder to provide a venturi effect whereby outward movement of air is facilitated.

THOMAS JACKSON.
